UNITED STATES PATENT OFFICE.

JOHN BRUDERER, OF PHILADELPHIA, PENNSYLVANIA, AND ORRIN CLARK BURDICT, OF BUFFALO, NEW YORK, ASSIGNORS TO PLUMB, BURDICT & BARNARD, OF BUFFALO, NEW YORK.

MACHINE FOR FORGING BOLT-BLANKS.

SPECIFICATION forming part of Letters Patent No. 310,646, dated January 13, 1885.

Application filed March 14, 1884. (No model.)

To all whom it may concern:

Be it known that we, JOHN BRUDERER, a citizen of Switzerland, residing at Philadelphia, in the county of Philadelphia and State of Pennsylvania, and ORRIN CLARK BURDICT, of Buffalo, in the county of Erie and State of New York, have made an invention of certain new and useful Improvements in Forging-Machines for Forging Bolt-Blanks, the Bars of Monkey-Wrenches, and Similar Articles; and we do hereby declare that the following, in connection with the accompanying drawings, is a full, clear, and exact description and specification of the same.

15 The object of our invention is, principally, to forge protuberant heads upon bars or rods of iron—such, for example, as the angular heads of machine-bolts when forged out of blanks of the size of their stems; and the invention consists of certain combinations of mechanical devices, which are recited in detail in the claims at the close of this specification.

In order that the invention may be fully understood, we have represented in the accompanying drawings, and will proceed to describe, the principal parts of a machine embodying our invention in the best mode devised by us up to the date of this specification, it being understood that the mechanism 25 of said machine may be greatly varied, as circumstances or the views of different builders or users render expedient.

Figure 1 of the said drawings represents a partial side view of the said machine, and 35 Fig. 2 represents a partial plan of the same. Figs. 3 to 6, inclusive, represent parts of the same detached from the residue and denoted by the same letters as they are in Figs. 1 and 2.

The machine to which we have applied our invention with success is that described and represented in the patent to O. C. Burdick, No. 168,135, dated the 28th day of September, A. D. 1875, and such parts of the machine as are not represented in our drawings and described herein are to be understood as to be 40 constructed as they are described and represented in said Burdick patent. The blank upon which the head is to be forged is applied to a blank-carriage, H, by means of which it 45 is moved forward between lateral forging-tools to the position to be operated upon by

a reciprocating heading-tool, and the head is forged by the combined action of the lateral forging and heading tools. Two lateral forging-tools, a a, are represented in the drawings, and we prefer to use two others, operating crosswise of said first two, (a a,) as in the said machine described in said Burdick patent. Two heading-tools, E E', are used in our machines, the one, E, to upset the head 55 in conoidal or globular form, and the second, E', to impart the finished form to the head. These two heading-tools are secured to a rocking die-holder, A, which in this example is fitted with lateral trunnions, a', which turn 60 in sockets formed in the cheeks of the head of a reciprocating piston, D. This piston is fitted to move endwise in guides secured to the bed-plate of the machine, so as to move with the die-holder and heading-tools toward 65 and from the blank-carriage. The piston is moved to and fro by means of a revolving crank-shaft, F, to which the pulley fly-wheel F' is secured, the connection between the crank-shaft F and the piston being a toggle- 70 rod, G.

In order to insure the requisite strength, the rocking die-holder A has a circular periphery, which bears in a curved seat in the head of the piston, so that the strain is borne by the 75 body of the shifting die-holder, and the trunnions are relieved in whole or in part of the strain of heading the bolt or other article. The two heading-tools E E' are caused to operate upon the blank in succession by shifting the position of the die-holder A relatively 80 to the piston G, which carries it, and the shifting being effected by causing the die-holder to turn upon the axis of its trunnions. In order that the rocking die-holder may be 85 turned on its axis to bring the heading-tools in succession into their positions for operating on the blank, and without affecting materially the reciprocating movement of the piston D, one of the trunnions of the die-holder is fitted 90 with a crank, c, which is connected by a link-bar, c', with one of the arms of a bell-crank, C, which is pivoted to the piston D. The other arm of the bell-crank has a pin, c', which is arranged to traverse in the slot of a movable 95 guide, B, which is moved up or down, as required, to turn the bell-crank and the rock-

ing die-holder in one direction or the other. Thus, when the first heading-tool, E, is in its acting position, as in Fig. 3, the movable guide is in its highest position, as in Fig. 3; but by depressing the guide, as in Fig. 1, the bell-crank and rocking die-holder are partially turned so as to occupy the positions represented in Fig. 1, and thereby turning the first heading-tool out of line with the bolt-blank *d*, and turning the second heading-tool into line therewith, as represented in Fig. 1.

In the machine represented in the drawings the blank-carriage H is caused to present the blank for the action of the heading-tools and lateral forging-tools, to hold it stationary during their operations or blows, and then to withdraw the headed blank so that it may be removed from the blank-carriage and a new unheaded blank may be substituted in its place. The first heading operation is effected while the first heading-tool, E, is in its heading position, as in Fig. 3. Then it is turned out of its heading position, and the second heading-tool is turned into its heading position, as in Fig. 1, and the remaining heading operations or blows are effected by it. The holding of the rocking die-holder in its position for the operation of the first heading-tool, the turning of the die-holder to bring the second heading-tool into its position for operating upon the blank, the holding of the second heading-tool in its heading position while the requisite number of blows are struck by it, and the turning of the die-holder backward so as to place the first heading-tool in position for operating upon the next new blank are effected by the cam J, which may be termed the "shifting-cam," and which operates through the elbow-lever J' upon the movable guide B, raising and lowering that guide and holding it stationary at the required times. The elbow-lever J' is fitted with a friction-wheel, which runs in the groove of the shifting-cam J, and the longer arm of the elbow-lever is fitted with a second friction-wheel, which is received in a slot formed in the shank of the movable guide B. The shifting-cam is fitted to revolve upon a stud, *j*, projecting from the frame of the machine, and it has a cog-wheel, K, secured to it, which is connected by a cog-wheel, shaft, and pinions, K² K³, with a cog-wheel, K', secured to the crank-shaft F of the machine, so that the said shifting-cam is turned once for every eleven revolutions of the crank of the machine. The blank-carriage is moved to present the blank to the lateral and heading dies, is retained in its position while the head of the blank is being forged, and is then withdrawn, so that the headed blank may be removed and a new blank may be put in its place.

The mechanism for moving the blank-carriage is substantially the same as that of the machine represented and described in the said Burdick patent, the carriage being connected by a toggle-link, P, with the arms of a rock-shaft, N. One end of the said rock-shaft has

a vibrating frame, O, fitted upon it and connected by a connecting-rod, *t*, with a crank-pir, S, secured to the crank-shaft of the machine, 70 so that the said frame is caused to vibrate continuously as the crank-shaft of the machine revolves. The rock-shaft, which moves the blank-carriage, is engaged with and disengaged from the rocking frame by means of the 75 double-headed pawl *w w'*, which turns upon a pivot of the vibrating frame, and is fitted to engage with either of two teeth, *v v'*, formed upon a hub, T, secured to the carriage rock-shaft N. When the pawl is turned so as to engage with the tooth *v*, the movement of the pawl by the vibration of the vibrating frame turns the carriage rock-shaft so as to advance the blank-carriage, and when the pawl is turned so as to engage with the tooth *v'*, the 80 movement of the pawl by the vibrating frame turns the carriage rock-shaft backward, so as to withdraw the blank-carriage. The pawl is held in either position, and is moved from one position to the other by the action of the 85 rim-cam J², which in this case forms part of and revolves with the shifting-cam J, and operates upon the lever J³, which is connected by a rod, *t'*, with an arm secured to the pivot of the double-headed pawl *w w'*. The lever J³ 90 has an arm, which is fitted with a friction-wheel upon which the rim-cam J² acts, and it is held in contact with the rim-cam by the action of the spring *f*. As the shifting-cam J (which turns and holds the turning die-holder) and the rim-cam (which determines the 95 movement of the blank-carriage and the time during which it remains in its advanced position) are connected together, the blank-carriage will always be advanced at the proper 100 time to have the bolt-blank receive its first heading blow from the first heading-tool, E, and the blank-carriage will be held in its advanced position while the blank receives the blow of the second heading-tool, E', after 105 which the blank-carriage will withdraw the headed blank, and will remain in its withdrawn position a certain length of time, determined by the form of the rim-cam J², thus giving time for the attendant to remove the 110 headed blank and apply an unheaded blank to the carriage. By changing the gear-wheels which connect the cams with the crank-shaft of the machine, and by changing the forms of the cams, the blank to be headed may be presented for a longer or shorter period to the action of the dies and heading-tools.

In order that the rocking die-holder and the heading-tools may be held securely in their operating positions during their action upon the blank, the fixed guide I is provided. It is arranged in this case at the outer side of the movable guide B, and the pin *c*² of the bell-crank is long enough to pass through the slot of the movable guide B and engage with 125 the fixed guide I. When the bell-crank is turned down, as in Fig. 1, and the heading-tools are moved forward, the projecting pin *c*² of the bell-crank passes beneath the fixed 130

guide I, which prevents the bell-crank from turning upward, and therefore holds the rocking die-holder and its heading-tools firmly in the positions which they then have—that is, 5 with the second heading-tool, E', in operating position. When the bell-crank is turned up and the heading-tools are moved forward, the projecting-pin c^2 of the bell-crank passes over the fixed guide I, which then prevents the bell-crank from turning downward, and therefore holds the rocking die-holder and its heading-tools firmly in the positions they then have with the first heading - tool, E, in its operating position. The fixed guide is shorter than 10 the stroke of the piston D, which carries the heading-tools and the bell - crank C; hence, when the piston is withdrawn about half its stroke the fixed guide no longer holds the arm c^2 of the rock-shaft, and the rock - shaft 15 may be turned to shift the positions of the heading-tools by the action of the movable guide B and the shifting-cam J.

In order that the two heading-tools may be readily applied to and removed from the shifting die-holder, they are applied and secured as represented more particularly in Fig. 4—that is to say, the second heading-tool has a round shank, e, which is received directly in a socket in the turning die - holder A, and it 20 is secured in this socket by means of a movable cup, e', which forms a socket for the first heading-tool, E, and has its inner end projected into a slot formed in the second heading-tool, E'.

35 The first heading-tool is held in its socket in the cup e' by means of a set-screw, e², whose point passes through a hole in the said cup and is engaged in the shank of the first heading-tool, and as this cup is held in place by 40 the same set-screw, e², which fastens the first heading-tool, both heading-tools are secured to the turning die-holder by the action of a single set-screw, e², which is in a position to be readily got at when the heading-tools are 45 to be loosed for removal or are to be fastened to the turning die-holder.

The parts of the machine which are not represented in the drawings and have not been specially described are constructed as set 50 forth in the said Burdick patent, No. 168,135.

In the machine thus described the shifting-cam and its connections with the movable guide, bell-crank, rod, and crank, secured to the shifting die-holder, constitute the devices 55 for shifting the die-holder so as to place each of its dies in its operating position at the required time. While we have used these devices for the purpose, we do not limit our invention to them, as other devices may be used 60 for the same purpose.

In order to relieve the shifting devices of strain during the heading operations, we make the groove of the shifting-cam J of the form to turn the rocking die-holder a little more 65 than a quarter of a revolution, and we construct the rocking die-holder with shoulders s , one of which abuts against a correspond-

ing shoulder, x , on the head of the piston D when each heading-tool is in its operating position, so that said abutting shoulders receive 70 the strain.

As the attendant may require a greater or less space of time to remove the forged blanks from the blank-carriage and to apply a new blank, we sometimes find it expedient to construct the machine so that it can be readily stopped and started. For this purpose we arrange the fly-wheel F' to revolve loose upon the crank-shaft F, and we connect it with the crank-shaft F by means of a clutch, M, Fig. 80 6, which can be thrown into and out of gear by means of a lever operated by a treadle or otherwise.

The combinations hereinafter recited in the second, third, fourth, and sixth claims are 85 restricted to that kind of a shifting die-holder which is rocked or moved in alternately opposite directions for the purpose of changing the positions of the dies, that kind of a die-holder being specially adapted to those combinations. In the combinations recited in the first, fifth, and seventh claims a die-holder constructed to be turned intermittently, but always in the same direction, may be substituted for a rocking die-holder. 90

We claim as our invention— 95

1. The combination, substantially as before set forth, of the reciprocating piston and its shifting die-holder with the movable blank-carriage which presents the blanks to the tool 100 carried by said shifting die-holder.

2. The combination, substantially as before set forth, of the reciprocating piston and its rocking die-holder with lateral forging-dies.

3. The combination, substantially as before 105 set forth, of the reciprocating piston, the rock-ing die-holder, the bell-crank connected with said die-holder, and the movable guide by which said bell-crank is controlled.

4. The combination, substantially as before 110 set forth, of the reciprocating piston, the rock-ing die-holder, and the fixed guide for lock-ing the die-holder in its several positions.

5. The combination, substantially as before 115 set forth, of the shifting die-holder, two head-ing dies, and a single set-screw.

6. The combination, substantially as before set forth, of the reciprocating piston fitted 120 with shoulders, and the shifting die-holder fitted with shoulders.

7. The combination, substantially as before set forth, of the reciprocating piston constructed with a curved seat for the shifting die-holder, with the shifting die-holder constructed with a curved periphery to bear in said seat 125 of said piston.

In witness whereof we have hereto set our hands this 13th day of February, A. D. 1884.

JOHN BRUDERER.
ORRIN CLARK BURDICT.
